UNITED STATES PATENT OFFICE.

JAMES V. BERGEN, OF EL PASO, TEXAS.

RAIL-FASTENING DEVICE.

986,348.

Specification of Letters Patent. Patented Mar. 7, 1911.

Application filed May 20, 1910. Serial No. 562,507.

To all whom it may concern:

Be it known that I, JAMES V. BERGEN, a citizen of the United States, and a resident of El Paso, in the county of El Paso and 5 State of Texas, have invented certain new and useful Improvements in Rail-Fastening Devices, of which the following is a specification.

My invention relates to improvements in 10 rail fastenings adapted to steel, concrete or composition railway ties, and it consists in the combinations, constructions and arrangements herein described and claimed.

An object of my invention is to provide 15 rail fastening and means for clamping rails to steel, concrete or composition railway ties without the use of bolts, screws, spikes or similar devices entering into the body of such ties and preventing the force of impact 20 blows upon the rails being concentrated at the point of rail contact.

A further object of my invention is to provide a device by means of which the rails may be clamped to the tie in such a manner 25 as to bring the strains on the ends of the tie instead of transverse thereto.

A further object of my invention is to provide fasteners which positively lock the 30 two rails together holding the same to alignment and gage as well as securely locked upon the tie, while at the same time acting to distribute the force of impact of passing 35 wheels over considerable surface at the end of the tie.

40 A further object of my invention is to provide a fastening for a steel, concrete or composition tie made rectangular in shape at its ends and rail bearings which is reversible end for end, or bottom for top, as desired.

Other objects and advantages will appear in the following specification, and the novel features of the device will be particularly pointed out in the appended claims.

45 My invention is illustrated in the accompanying drawings, in which—

Figure 1 is a side view of the tie, the rails being shown in sections, Fig. 2 is a plan view, Fig. 3 is an enlarged section along the 50 line 3—3 of Fig. 2, and Fig. 4 is a perspective view of the bolt and strap for securing the clamps to the upper part of the tie.

In carrying out my invention, I provide a tie of the form shown in the drawing. This, 55 if a concrete or composition tie, consists of a body portion A having embedded therein

reinforcing bars a around which is wound turns of wire b. The tie is preferably of octagonal shape along its middle portion, as shown in Figs. 1 and 2. At the ends of 60 each tie is a plate C which is bent to form two recesses c.

The rail clamps comprise a metal plate D provided with side flanges d, or other excess of metal to reinforce the angle. This 65 plate has an extension at its end as shown at d' which has a portion d² bent inwardly. The portion d² is designed to enter one of the recesses c. The opposite end of the plate D has two bent portions forming retaining 70 members for the base of the rail. These retaining members are shown at d³. Between the members d³ is an integral connecting portion d⁴ which terminates in a plate E which is bent up at its end e to form a retaining member for the opposite rail. 75

As will be seen from Figs. 1 and 2, the companion clamping members D', E', etc., are turned in the opposite direction. Thus, the retaining member e' of the plate E' is in 80 engagement with the rail 1, while the retaining members d³' are in engagement with the rail 2.

In Fig. 4 I have shown means for retaining the clamping members in their proper 85 position. This comprises a bolt F passing through a plate G having recesses g adapted to receive the members d⁴ and d⁴' said bolt also passing through the body of the tie. 90

From the foregoing description of the various parts of the device the operation thereof may be readily understood. In placing the rails upon the ties the clamping members which have been arranged on the 95 rails, are slid along until their ends d² and d²' register with the recesses c into which they pass. A wedge K is now driven in between plate C and the downwardly turned end of the member D thus drawing the 100 clamping member toward the end of the tie and causing the retaining members d³ and e to engage the base flanges of the rails 1 and 2. The companion clamping member is then brought into position and a wedge K 105 is driven home so as to bring the retaining member e' and d³' into engagement with the rails 1 and 2 respectively, clamping them securely between these retaining members and their companion retaining members d³ and e. In order to further secure the clamping members the bolts F are 110

passed through pipes in the tie, the straps G fitting over the clamping members and securely binding them to the tie when the nuts f are turned to force the straps downwardly. The bolts F being fitted loosely can have the nuts either above or below the tie.

From the description of the tie, it will be seen that the rails are really held by the 10 ends of the ties so that the force of impact is taken up by the ends of the ties largely.

If the tie should become worn on top, it may be reversed and the rail secured on the other side, since the retaining members d² 15 and d²' will now enter the other recesses c.

I claim:

1. In a tie for railways, a main body portion provided with recesses, a clamping member comprising a plate adapted to lie 20 on top of the tie and having an extension at one end provided with a bent portion adapted to enter one of said recesses, retaining members adapted to engage the rails, and a wedge for drawing said retaining members 25 into engagement with the rail.

2. In a tie for railways, a main body portion provided with recesses, a clamping member having a bent portion at one end adapted to enter one of said recesses, retaining 30 members adapted to engage the rails, and a wedge for drawing said retaining members into engagement with the rail.

3. In a tie for railways, a main body portion provided with recesses at its ends, a clamping member comprising a plate adapted 35 to lie on top of the tie and having an extension at one end provided with a bent portion adapted to enter one of said recesses, retaining members carried by said clamping member, and a wedge adapted to be driven 40 between the end of the tie and the lateral extension of said clamping member for forcing said retaining members against the rail.

4. In a tie for railways, a main body portion provided with plates at its ends having recesses therein, a pair of clamping members each comprising a plate adapted to lie on the top of a tie having an extension at one end provided with a bent portion adapted 45 to enter one of said recesses, retaining members carried by said clamping member, said clamping members being secured by said extension at opposite ends of the tie, and wedges adapted to be driven between the end plates and the extension of said 50 clamping members for forcing the retaining members of each of said clamping members in opposite directions, thereby clamping the rails.

JAMES V. BERGEN.
